(57) CLAIM

The ornamental design for a component of a holder and storage device for reagent tubes, as shown and described.

DESCRIPTION

FIG. 1 is a front view of a component of a holder and storage device for reagent tubes in an open position;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and

FIG. 8 is a front view of a component of the holder and storage device for reagent tubes in a closed position;

FIG. 9 is a rear view thereof;

FIG. 10 is a left side view thereof;

FIG. 11 is a right side view thereof;

FIG. 12 is a top view thereof; and,

FIG. 13 is a bottom view thereof.

The broken lines depict portions of the component of a holder and storage device for reagent tubes that form no part of the claimed design.

1 Claim, 13 Drawing Sheets
